CLAIM

The ornamental design for a grilling stone, as shown and described.

DESCRIPTION

The present invention claims priority to U.S. patent application Ser. No. 12/692,766, entitled “Grilling Apparatus and Methods of Making and Using the Same,” filed Jan. 25, 2010. FIG. 1 is a front isometric view of a grilling stone showing my new design;

FIG. 2 is a top view thereof;

FIG. 3 is a bottom view thereof;

FIG. 4 is a front view thereof, with shading illustrating contour of the surfaces;

FIG. 5 is a rear view thereof, with shading illustrating contour of the surfaces;

FIG. 6 is a right side view thereof, with shading illustrating contour of the surface; and,

FIG. 7 is a left side view thereof, with shading illustrating contour of the surface.
